ABSTRACT OF THE DISCLOSURE

A davit having a davit arm mounted on the deck of a ship, with at least two ropes connected to each point suspension of an object to be handled, one of the ropes extending to a sheave mounted near the top of the arm, the other rope extending to a sheave mounted on the arm at a certain distance from the top sheave, such that at each point of suspension the object is supported in the inboard position of the davit arm by the one rope and at the outboard position of the arm by both ropes.

The invention relates to a davit for launching from or for taking on board of a ship, a life boat, a landing craft, a launch, a raft, a buoy, a mine, a torpedo, an ambulance or a similar object, said davit comprising a davit arm for supporting the object, said arm being mounted on the deck of said ship in such a way that it is adapted to take an inboard position for stowing said object and an outboard position for raising or lowering said object, means for bringing said davit arm from the one position in the other and vice versa, means for lowering and raising said object including falls, at least one winch for winding up and paying out said falls and/sheaves for guiding said falls between said object and said winch.

The difficulty in handling such objects with a davit as described is that in the case when the ship is rolling during the raising or lowering of the object it can strike heavily against the ship.

The invention has for its object to provide a davit with which the risk of an accident as a result of the impacts between the object and the ship is minimized. According to the invention at each point of suspension of said object at least two falls are connected to said object, one of said falls extending from said point to a sheave mounted near the top of said davit arm, the other fall extending from said point to a sheave mounted on said arm at a certain distance from said top sheave, such that in each point of suspension in the inboard position of said arm, said one fall supports said object and in the outboard position of said arm both falls support said object, said one fall extending upwards in a direction away from the ship and said other fall extending upwards towards the ship.

During the lowering and raising of the object the one fall pulls the object away from the ship and the other fall pulls the object towards the ship. Due to this arrangement a swinging movement of the object is prevented or at least damped to a great extent.

In an advantageous embodiment of the invention, said sheaves for guiding said falls from the point of suspension are arranged on said arm at such a distance from each other that in the outboard position of said arm said top sheave lies outside the ship at a distance which is at least corresponding with the width of said object, whereas said other sheave is lying just outside the ship.

Further according to the invention the winches for winding up and paying out said falls are synchronized.

The invention is elucidated further with reference to the drawing, which illustrates some embodiments of the davit according to the invention.

2

In the drawing:

FIG. 1 shows a davit according to the invention with a lifeboat in a section across a ship;

FIG. 2 shows the davit of FIG. 1 in a view transverse to the ship;

FIG. 3 shows a davit with a lifeboat in other embodiment in a section across a ship;

FIG. 4 shows the davit of FIG. 3 in a view transverse to the ship; and

FIG. 5 shows a davit with a buoy or the like in a section across a ship.

In FIGS. 1 and 2 a gravity davit is shown which is inserted for pivoting on the deck of a ship. The davit arm 1, 2 can swing out from the inboard position shown in solid lines to the outboard position shown in chain dotted outline at 1', 2' under the influence of gravity, said swinging being controlled by a winch 3 mounted on the arm 1. The winch 3 has two drums 4, 5 which are mounted on one shaft 6. On the drum 4 a steel rope 7 is wound, said rope 7 being guided by a sheave 8 mounted on the arm 1 and being connected to a fixed point 9 on the deck 10 near the davit arm 1. On the other drum 5 a steel rope 11 is wound, said rope 11 being guided by sheaves 12, 13, 14 and connected to a fixed point 15 on the deck 10 near the davit 2.

The drums 4, 5 have the same diameter so that by operating these drums 4, 5 the davit arms 1, 2 are moved in synchronized way, therefore the davit arms 1, 2 can be connected by a cross beam 16 which can resist the horizontal forces arising from the pull in the rope 11 between the davit arms 1, 2.

A lowering winch 17 is also mounted on the davit arm 1. On the drum 18 of winch 17 falls 19, 20 are wound. These falls 19, 20 are guided by sheaves 21, 22 resp. 23 mounted on the davit arm 1 and are connected to a ring 24.

On the drum 25 the falls 26, 27 are wound, which are guided by sheaves 28, 29, 30, 31 resp. 32, 33, 34 and are connected to a ring 35. The drums 18, 25 are mounted on one shaft 36 and have the same diameter so that the movement of the falls 19, 20, 26, 27 is substantially synchronized. The sheaves 22, 23 resp. 31, 34 are positioned in such a way that in the inboard position of the arms 1, 2 the one fall 19, 26 is tensioned and the other fall 20, 27 is slack.

When the boat 37 is suspended by means of the rings 24, 35, and is to be launched, it is only necessary to loosen the brake. Preferably the length of the steel ropes 7, 11 is such that in the outboard position of the davit arms 1, 2 the ropes 7, 11 are completely unwound from the drums 4, 5 but remain connected to these drums 4, 5 which are stopped in their "dead center." In this way no shock will occur when the arms 1, 2 reach the outboard position. In the outboard position of the arm 1' the fall 20 is tensioned due to the rotation of the arm 1. The fall 19' is pulling the ring 24' away from the ship whereas the other fall 20' is pulling the ring 24' towards the ship. Similar considerations are true for the arm 2 and the ring 35. So the rings 24', 35' are in a definite position which is adapted for embarkation of the boat 37'. Upon a further lowering of the boat to the position shown at 37'' the distances 22', 24' and 23', 24' remain the same, so that the distance between the ring 24' and the side of the ship remains also the same.

The lifeboat can rotate around an axis through the rings 24'', 35'', but remains inside the circle 38 around the rings 24'' 35''. In this way contact of the boat 37'' with the ship can be prevented for rolling movements which do not exceed the angle 22', 24', 23'. It is easy to imagine that in the case when the ship is very high above the water level and the davit arms 1, 2 are rather

short, the angle 22', 24", 23' will be rather small so that it is possible that the boat 37" strikes against the ship when strong rolling movements occur. In such a way the arrangement has still its effect. The angle between the falls 19', 20' is great during the first part of the lowering movement and even when the angle between the falls becomes very small, the swinging movements of the boat are effectively damped.

In FIGS. 3 and 4 similar parts are indicated with the same numerals as in FIGS. 1 and 2.

In this embodiment the boat 37 is suspended on the davit arms 1, 2 which can move by means of rolls 39, 40 along track 41, 42 which are mounted on the deck 10 of the ship. On the tracks 41, 42 davit control winch 3 is mounted and the ends of steel ropes 7, 11 are connected to the moving parts at 43, 44 and are directly and indirectly connected with the arms 1, 2. The davit control winch 3 consists of two parts, one with a drum 4 for the davit arm 1 and the other with the drum 5 for the arm 2. Both drums 4, 5 are synchronized by means of the shaft.

The lowering winch 17 also consists of two parts. The drums 18, 45 control the falls 19 and 20, whereas the drums 46, 25 control the falls 26, 27. The four drums 18, 45, 46, 25 are synchronized by means of the shaft 47, which moves with the davit arms 1 and 2. In general it can be remarked that the lowering winch 17 can be combined with the davit arm control winch 3.

FIG. 5 shows a single davit for a raft, a buoy a mine or a similar object. The davit arm 1 is hingedly connected to a rotating column 47 which is mounted around a shaft 48 which is mounted on the deck 10. The davit arm 1 is held in position by means of a winch 3 with a drum 4 and a steel rope 7 which is guided by a sheave 8 and is connected to the arm 1.

A lowering winch 17 is mounted on the davit arm 1. On the drum 18 of this winch 17 are wound two falls 19, 20 which are guided by the sheaves 22 and 23 and are connected at their free ends to a ring 24 which is connected to a buoy 50.

The sheaves 22, 23 are positioned on the arm 1 in such a way that upon paying out the falls 19, 20 the ring 24 is lowered substantially parallel to the side of the ship. Small deviations in the path of the ring 24 can be corrected by winding the falls 19, 20 on drums of a different diameter.

I claim:

1. A davit for launching or for taking on board a ship, a lifeboat, a landing craft, a launch, a raft, a buoy,

a mine, a torpedo, an ambulance or a similar object, said davit comprising a davit arm supporting the object, means mounting said arm on the deck of said ship such that the arm is adapted to take an inboard position for stowing said object and an outboard position for raising or lowering said object, means for bringing said davit arm from one position to the other, means for lowering and raising said object including falls, at least one winch for winding up and paying out said falls and sheaves for guiding said falls between said object and said winch, wherein at each point of suspension of said object at least two separate falls are connected to said object, one of said falls, extending from said point to a sheave fixedly mounted near the top of said davit arm, the other fall extending from said point to a second sheave fixedly mounted on said arm at a distance from said top sheave, such that at each point of suspension in the inboard position of said arm said one fall supports said object and in the outboard position of said arm both falls support said object, said one fall extending upwardly in a direction away from the ship and said other fall extending upwards toward the ship.

2. A davit according to claim 1, wherein said sheaves for guiding said falls from said point of suspension are spacedly arranged on said arm at such a distance from each other that in the outboard position of said arm said top sheave lies outside the ship by a distance which at least corresponds with the width of said object, whereas said other sheave lies just outside the ship.

3. A davit according to claim 1 comprising means connecting the winches which wind up and pay out said falls for synchronized movement.

4. A davit according to claim 1 comprising a ring at each point of suspension secured to said object, the two falls at each point of suspension being connected to said ring thereat.
